PUNCH CORE ORIENTER FOR WELLS

Manley Leonard Natland, Rolling Hills, and Raymond E. Pearson, Compton, Calif., assignors to Richfield Oil Corporation, Los Angeles, Calif., a corporation of Delaware

Application December 13, 1948, Serial No. 65,024

9 Claims. (Cl. 255—1.4)

1

The invention relates to apparatus for taking cores from wells and is particularly directed to improvements in punch core apparatus to provide means for orienting the core.

The principal object of this invention is to provide an improved punch core apparatus which is insertable and retractable through a drill string and without requiring that the drill string be removed from the well bore.

Another object is to provide a nonrotary core barrel device having means for determining the orientation of the core.

Another object is to provide a device of this type for use in slant holes and employing a ball which rolls to the low side of an annulus for subsequent impression into a soft washer to indicate orientation of the core.

A further object is to provide a punch core orienter for use in substantially vertical holes and provided with an inclinometer for indicating the azimuth and inclination of the punch core device in operative position.

Other objects and advantages will appear hereinafter.

In the drawings:

Figure 1 is a longitudinal sectional elevation showing a retractable core barrel latched in position at the lower end of a drill string which extends into a well bore.

Figure 2 is a sectional elevation on an enlarged scale showing the lower end of a preferred form of punch core barrel device embodying our invention.

Figure 3 is a sectional plan view taken substantially on the lines 3—3 as shown in Figure 2.

Figure 4 is a sectional view similar to Figure 3 showing a modified form of our invention.

Figure 5 is a longitudinal sectional view showing a further modification of the lower end of the punch core barrel.

Figure 6 is a sectional plan view taken substantially on the lines 6—6 as shown in Figure 4.

Conventional coring devices commonly employ a core bit with a hollow center which cuts away an annular ring into the formation, leaving the center of the hole uncut and forming a projection which extends upwardly into a core barrel extending downwardly into the hollow bit. When the desired length of core has been received within the core barrel, the core barrel, together with the formation sample or core, is withdrawn to the surface. The core barrel may be withdrawn on a wire line through the interior of the drill string or the drill string itself may be withdrawn section by section to bring the core barrel to the

2

surface. In either event, a problem of orienting the core arises in order to determine the azimuth of the dip of the well formation. The present invention relates to punch core apparatus in which the core barrel is provided with a cutting head and is moved longitudinally into the formation without rotary motion. A device is provided on the retractable assembly which furnishes a record of the inclination of the device at the time of taking the core from the formation. The retractable device then is withdrawn from its position at the lower end of the drill string and is lifted through the interior of the drill string to the surface. The angular position of the core within the core barrel is then noted and the record of the inclination of the device as furnished by the inclinometer is inspected. From this information the orientation of the core with respect to the formation can readily be determined.

10 In bore holes where the angle of inclination has not been independently determined by surveys, we prefer to mount a "single shot" survey instrument within the retractable device. This single shot instrument may be of conventional form and need not be described in detail herein. It functions to provide a measure of the inclination and azimuth of the retractable device at the time the punch core is taken.

Where the azimuth and angle of inclination 30 of the well bore are known from surveys, and where the angle of inclination of the bore hole varies from the vertical by more than three degrees approximately, we prefer to utilize a relatively simple type of indicator instead of a single shot survey instrument. This indicator provides a record of the "low side" of the retractable device so that by correlation with the known inclination and direction of the bore hole the orientation of the core may be determined.

40 Referring more particularly to the detailed construction of the embodiments of our invention as shown in the drawings, the bore hole 10 receives the drill string generally designated 11 which may be composed of a plurality of sections 12 threaded end to end. The lowermost section or sections commonly has a heavier wall thickness and is known in the art as a drill collar 13. A bit 14 is connected to the lower end of the drill collar, and as shown in Figure 1 this bit 50 may be provided with an axial opening 15 through which the retractable core barrel assembly 16 may extend. The assembly 16 includes a shell 17 secured to the lower end of a connection fitting 18. This connection fitting is in turn carried by 55 the lower end of a tubular support 19. A body

20 carried within the shell 17 extends downwardly therefrom to enclose the core-receiving tube 21. This tube may be longitudinally split on one side from end to end if desired in order to facilitate extraction of the core. A cylindrical cutter 22 having a sharpened lower end 23 is secured in place on the lower extension 24 of the body 20 by means of the securing nut 25. A frangible pin 26 extends through aligned openings provided in the body 20 and sleeve 17, and in this position the annular shoulder 27 on the body rests on the cooperating annular shoulder 28 on the sleeve. The cylindrical surfaces 29 and 30 on the body are received in sliding engagement within the cylindrical bores 31 and 32 respectively within the sleeve 17.

A soft annular ring 33 which may be formed of aluminum or other soft material is mounted on the upper end of the body 20 and keyed thereto by means of a pin 34. The ring 33 may be held in place by means of the retaining nut 35 threaded on the upper end of the body. A spherical element 36 which may comprise a steel ball rolls on the ring 33 within the annulus 37 defined between the retaining nut 35 and the bore 31 of the shell 17. When the weight of the drill string 11 is applied to the retractable assembly 16 the cutter 22 is forced into the formation so that a core is driven upwardly into the core-receiving tube 21. The force on the cutter shears the frangible pin 26 and allows the body 20 to move upwardly within the shell 17. The annular abutment 38 on the lower end of the connection fitting 18 then drives the steel ball 36 into the relatively soft annular ring 33. Since the ball rolls to the low side of the annulus 31, the impression made by the ball in the ring 33 forms a record of the direction of inclination at the time the core was taken. After the ball 36 has been driven into the soft ring 33 the cooperating surfaces 39 on the members 35 and 18 meet in metal-to-metal relationship so that the load applied to the cutter 22 is carried principally on these cooperating surfaces and not by the ball 36.

The upper end of the tubular support is carried on the latch body 40. This latch body 40 forms a part of a latch assembly generally designated 41 which may take any conventional form. As shown in the drawings, a latching lug 42 is pivotally carried on the latch body at 43 and is adapted to extend under a shoulder 44 fixed relative to the drill string 11. A pull bar 45 is slidably mounted relative to the latch body 40 and carries a cross-pin 46 operable in an angularly disposed slot 47 provided in the latching lug 42. When the knob 48 on the upper end of the pull bar 45 is engaged by the overshot 49 and lifted vertically, the pull bar 45 moves upwardly relative to the latch body 40, causing the cross-pin 46 acting in the slot 47 to retract the latching lug 42 so that it no longer underlies the stationary shoulder 44. Continued upward movement of the overshot 49 serves to retract the entire device 16 through the drill string 11. The overshot 49 may be carried on the end of a wire line operated in a conventional manner.

The form of the invention just described and illustrated in Figures 2 and 3 is useful in connection with bore holes which are more than 3° approximately off the vertical. In such holes there is sufficient angularity to cause the steel ball 36 to roll to the low side of the annulus 37 and hence provide an accurate record of the low side of the device when the ball is impressed into the soft washer 33. For holes having less an-

gularity, that is, for holes more nearly vertical, the ball cannot be relied upon to give accurate results. In slant holes, however, which have been previously surveyed to determine orientation of the bore hole this relatively simple device affords an accurate means of orienting the core in order to determine the direction of dip of the formation. The pin 34 serves to key the soft annular washer 33 relative to the body 20 and the pin 58 on the body enters the slot 51 on the core tube 21 to align the core tube with the body 20. A short marker pin 52 may be provided on the cutter 22 adjacent the sharpened lip 23 so that a scratch mark is formed on the core as it enters the cutter on its way into the core tube 21. Aligned openings 53 are provided on the cutter 22 for reception of a pin 54. A pin 55 is passed through the aligned openings 56 in the shell 17 and body 20. Prior to insertion of the assembly 16 into the upper end of the drill string 11 the pins 54 and 55 are aligned so that they lie in the same plane. The pins 54 and 55 are then withdrawn and the retractable core barrel assembly is ready for use.

It will be understood that during normal drilling operations a small center bit (not shown) is inserted into the main bit 14 and latched in position so that the full area of the bottom of the bore hole is acted upon. This center bit is retracted prior to installation of the assembly 16.

In that form of our invention shown in Figures 4 and 6 the shell 70 is connected to the body 71 by means of the frangible pin 72. The body 71 is threaded at its lower end to connect to a central housing 73. This housing encloses a conventional single shot surveying instrument generally designated 74. This instrument 74 is preferably shock mounted between cushions 75 and 76. A wedge-shaped key element 77 extends downwardly from the instrument into a correspondingly shaped recess 78 provided in the upper end of the tubular member 79 which forms a lower extension of the housing 73. A core tube support 81 is attached to the lower end of the member 79. Conventional spring guides 83 may be provided if desired on the outer surface of the core tube support 81. The core tube 84 is mounted within the support 81 and held against rotation by the cooperative engagement of the pin 85 with the slot 86. The cutting head 87 is connected to the support 81 by means of the threaded joint 88 and serves to maintain the core tube 84 in position. The pins 80 and 82 may be inserted into transverse openings provided in the tubular member 79 and cutting head 87 respectively and aligned so that they lie in the same plane. These pins 80 and 82 are withdrawn prior to insertion of the device into the drill string.

In operation the retractable core barrel assembly as shown in Figure 4 is latched into position at the lower end of the drill string by means of any suitable latch means such as, for example, as shown in Figure 1. The sleeve 70 and each of the parts positioned therebelow, with the exception of the cutting head 87, are preferably formed of nonmagnetic material in order that magnetic direction indicating mechanism contained within the unit 74 may operate satisfactorily. Furthermore, the sleeve 70 projects downwardly through the opening in the bit on the lower end of the drill string so that the single shot instrument 74 is positioned below the steel parts of the drill string 11. With the device latched in position the drill string is low-

ered to bring the cutting head 87 into contact with the bottom of the well bore. The weight of the drill string fractures the frangible pin 72, permitting the body 71 to move upwardly within the sleeve 70 until it strikes the shoulder 89. The weight of the drill string then forces the pointed end 90 of the cutting head 87 into the formation so that a core is received in the core tube 84. The assembly is unlatched from the drill string and withdrawn on a wire line as described in connection with the previous modification. The core is marked by means of the pin 91, and since the angular relationship between the pin 91 and the single shot instrument 74 is known the orientation of the core may be readily determined. While the single shot instrument 74 may take any conventional form, we prefer to employ a device of this type which may be set to operate at a predetermined time. In order to be sure that the instrument has operated to provide a record of the inclination and direction of the retrievable assembly, it is only necessary to allow the required time interval to elapse before withdrawing the assembly from the drill string.

In Figure 5 we have shown a modified form of cutting head assembly. The cutting head 100 is threaded to a collar 101. A retaining nut 102 engages the abutment 103 on the lower end of the collar and serves to clamp the collar 101 against the lower end of the core tube support 104. When it is desired to align the bar 105 with the pin 80 the retaining nut 102 is turned in an unthreading direction through a small angle to relax the clamping effect on the collar 101 and thereby permit the cutter 100 and its marking to be properly oriented. The bar 105 is held in alignment with the pin 80 while the nut 102 is retightened. This insures that the marking pin is correctly oriented with respect to the single shot instrument 74.

Having fully described our invention, it is to be understood that we do not wish to be limited to the details herein set forth, but our invention is of the full scope of the appended claims.

We claim:

1. In a device insertable through a drill string for taking a punch core from a well bore and for indicating orientation of the core, the combination of a retrievable core barrel assembly adapted to be lowered from the surface through the drill string; means for latching the core barrel assembly relative to the drill string at a location adjacent its lower end; a portion of said assembly in latched position projecting below the lower end of the drill string means carried on said projecting portion of the retrievable core barrel assembly for providing a record of the direction and inclination of the core barrel assembly in latched position; a tubular member on the core barrel assembly positioned below said means so that a punch core may be taken by the member upon lowering of the drill string; and means for withdrawing the core barrel assembly and core upwardly through the drill string.

2. In a device insertable through a drill string for taking a punch core from a well bore and for indicating orientation of the core, the combination of a retrievable core barrel assembly adapted to be lowered from the surface through the drill string; means for latching the core barrel assembly relative to the drill string at a location adjacent its lower end; means carried on the retrievable core barrel assembly for providing a record of the direction of inclination 75

of the core barrel assembly in latched position, said means including a gravity responsive member adapted to be impressed into a relatively soft element; a tubular member on the core barrel assembly projecting for its full length below the lower end of the drill string so that a punch core may be taken by the member upon lowering of the drill string; and means for withdrawing the core barrel assembly and core upwardly through the drill string.

3. In a device insertable through a drill string and bit for taking a punch core from a well bore and for indicating orientation of the core, the combination of a retrievable core barrel assembly adapted to be lowered from the surface through the drill string; means for latching the core barrel assembly relative to the drill string at a location adjacent the bit; a portion of the retrievable core barrel assembly in latched position projecting below the lower end of the drill string; recording means carried on the said projecting portion of the retrievable core barrel assembly for providing a record of the inclination of the core barrel assembly in latched position; and a core-receiving member on the core barrel assembly projecting for its full length below the lower end of the bit so that a punch core may be taken by the member upon lowering of the drill string.
4. In a device insertable through a drill string and bit for taking a punch core from a well bore and for indicating orientation of the core, the combination of a retrievable core barrel assembly adapted to be lowered from the surface through the drill string; means for latching the core barrel assembly relative to the drill string at a location adjacent the bit; a portion of the retrievable core barrel assembly in latched position projecting below the bit; recording means carried on the said projecting portion of the retrievable core barrel assembly for providing a record of the inclination of the core barrel assembly in latched position; a core-receiving member on the core barrel assembly projecting for its full length below the lower end of the bit so that a punch core may be taken by the member upon lowering of the drill string; a marker element on said member adapted to mark the core as it enters said member; and means to adjust the relative angular position of said marker element and said recording means.
5. In a device insertable through a drill string and bit for taking a punch core from a well bore and for indicating orientation of the core, the combination of a retrievable core barrel assembly adapted to be lowered from the surface through the drill string; means for latching the core barrel assembly relative to the drill string at a location adjacent the bit; recording means carried on the retrievable core barrel assembly for providing a record of the inclination of the core barrel assembly in latched position; the core barrel assembly including a shell slidably received within the bit and a body slidably mounted within the shell; axially spaced shoulders on the shell and body; a frangible pin connecting the shell and body; and a core-receiving member on the body extending for its full length below the bit so that a punch core may be taken by the member upon lowering of the drill string to shear said pin and bring said shoulders into engagement.
6. In a device insertable through a drill string and bit for taking a punch core from a well bore and for indicating orientation of the core, the

combination of a retrievable core barrel assembly adapted to be lowered from the surface through the drill string; means for latching the core barrel assembly relative to the drill string at a location adjacent the bit; the core barrel assembly including a shell slidably received within the bit and a body slidably mounted within the shell; recording means including a gravity responsive member adapted to be impressed into a relatively soft element; said recording means being carried on the core barrel assembly and actuated by relative movement of the body and shell to provide a record of the inclination of the core barrel assembly in latched position; axially spaced shoulders on the shell and body; a frangible pin connecting the shell and body; and a core-receiving member on the body extending for its full length below the bit so that a punch core may be taken by the member upon lowering of the drill string to shear said pin and bring said shoulders into engagement.

7. In a device insertable through a drill string and bit for taking a punch core from a well bore and for indicating orientation of the core, the combination of a retrievable core barrel assembly adapted to be lowered from the surface through the drill string; means for latching the core barrel assembly relative to the drill string at a location adjacent the bit; the core barrel assembly including a shell slidably received within the bit and a body slidably mounted within the shell; recording means for providing a record of the inclination of the core barrel assembly in latched position, said recording means including a gravity responsive member and a relatively soft element both operatively interposed between the shell and body; axially spaced shoulders on the shell and body; a frangible pin connecting the shell and body; and a core-receiving member on the body extending for its full length below the bit, so that lowering of the drill string shears the pin, imbeds the gravity responsive member in the relatively soft element and brings the shoulders into engagement.

8. In a device insertable and retractable through a drill string for taking a punch core from a well bore and for indicating orientation of the core, the combination of a retrievable core barrel assembly adapted to be lowered

from the surface through the drill string; means for latching the core barrel assembly relative to the drill string at a location near its lower end; a portion of said retrievable core barrel assembly in latched position projecting below the lower end of the drill string; means carried on said projecting portion of the retrievable core barrel assembly for providing a record of the inclination of the core barrel assembly in latched position; a core-receiving member on the core barrel assembly projecting for its full length below the lower end of the drill string and adapted to take a punch core upon lowering of the drill string; and means for unlatching and withdrawing the core barrel assembly and core upwardly through the drill string.

9. In a device for taking a punch core from a well bore and for indicating orientation of the core, the combination of a drill string having a bit at its lower end; a retrievable core barrel assembly adapted to be lowered from the surface through the drill string; means for latching the core barrel assembly relative to the drill string at a location adjacent the bit; a portion of said core barrel assembly in latched position projecting below the bit; means carried on said projecting portion of the core barrel assembly for providing a record of the inclination of the core barrel assembly in latched position; a member on the core barrel assembly projecting for its full length below the bit so that a punch core may be taken by the member upon lowering of the drill string; and means for withdrawing the core barrel assembly and core upwardly through the drill string.
